Primary Examiner — Shannon W Morgan*Assistant Examiner* — Terilyn Davis(74) *Attorney, Agent, or Firm* — Jacob M. Ward; Ward Law Office LLC(57) **CLAIM**

The ornamental design for an eating utensil, as shown and described.

DESCRIPTIONFIG. 1 is a top perspective view of an eating utensil;
FIG. 2 is a top plan view thereof;

FIG. 3 is a bottom plan view thereof;

FIG. 4 is a left-side elevational thereof;

FIG. 5 is a front elevational view thereof; and,

FIG. 6 is a back elevational view thereof.

A right-side elevational view is not shown because it is a mirror image to the left elevational view shown in FIG. 4.
